Primary Examiner — Elizabeth A. Albert(74) Attorney, Agent, or Firm — Dunlap Bennett & Ludwig PLLC(57) CLAIM

The ornamental design for a hanging organizer with pockets, as shown and described.

DESCRIPTION

FIG. 1 is a front perspective view of a hanging organizer with pockets, showing my new design;

FIG. 2 is a front elevation view thereof;

FIG. 3 is a rear elevation view thereof;

FIG. 4 is a right-side elevation view thereof, the left-side elevation view being a mirror image thereof;

FIG. 5 is a top plan view thereof; and,

FIG. 6 is a bottom plan view thereof.

The broken lines shown in the drawings depict portions of the hanging organizer with pockets that form no part of the claimed design.
